DETACHABLE BATTERY TERMINAL

Filed Dec. 28, 1927

1. 用直尺量出每根小棒的长度。

ATTORNEY

UNITED STATES PATENT OFFICE

DANIEL H. SCHLAEGEL, OF WADENA, MINNESOTA

DETACHABLE BATTERY TERMINAL

Application filed December 28, 1927. Serial No. 243,163.

The present invention relates to battery terminals and has for its object to provide a terminal which may quickly and easily be attached to the binding post of a battery and which will avoid breakage due to the attaching of the ordinary attachments now in use.

Other objects are simplicity of construction, cheapness of manufacture, and effectiveness in operation.

Other objects and advantages will appear from the following specification and will be set forth in the appended claim, and I do not wish to be limited in the scope of my invention except as I shall be limited by said

claim.

In the drawings:

Figure 1 is a plan view showing fragmentarily the top of a storage battery with my invention attached to one of the binding posts thereof.

Figure 2 is a view showing my invention detached from the battery.

Figures 3 and 4 are the gripping arms of my device.

Figure 5 is a view similar to Figure 2 of a modified form of the invention.

Referring to the drawings in detail, 10 designates a storage battery having a binding post 11, and 12 designates the terminal attachment constituting the subject of my invention. This device comprises a pair of members 13 and 14 having comparatively straight portions 15 and 16 and semi-circular portions 17 and 18, the former lying in substantial parallelism with each other and the latter being adapted to grip therebetween a binding post of a battery, as shown in Figure 1. The lower end of one of the curved portions 17 is provided with an aperture 19 adapted to receive therethrough the projection 20 formed at the lower end of the portion 18 of the member 14. The aperture 19 is of sufficient size compared with the projection 20 to permit of limited pivotal movement of the member 14 relative to the member 13.

Pivots secured to the portion 15 of the member 13 are links 21, said links being secured to the member 13 by means of a pin 22 passing through aligned apertures in the

ends of the links and in the portion 15 of the member 13. The opposite ends of the links are also apertured and connected with each other by a pin 23, upon which is rotatably mounted a cam 24.

The member 14 is provided in the region designated by the numeral 16 with a depression 25 adapted to receive therein a rounded portion 26 of the cam when the same is in locking position. The cam is provided with an elongated portion 27 having a finger grip 28 formed thereon, adapting the same for easy release when gripping the post of the battery.

The member 13 is provided at its upper end with a tubular portion 29 formed by bending the metal thereof rearwardly into a cylinder with the adjacent edges thereof slightly spaced apart as shown in Figure 3. A conductor 30 is attached thereto by inserting the end into the cylindrical portion of the member 29 and bending the members 31 thereof about the conductor.

In operation, when it is desired to place the terminal on the binding post of a battery, it is merely necessary to turn the cam to the position as illustrated in Figure 2, allowing the gripping jaws 17 and 18 to spread apart at their upper end by a pivotal movement about the connection between the portion 20 and the opposite apertured end of the member 13. When the device is placed over the binding post the cam is then moved to the position shown in Figure 1, in which position it will remain until moved by an operator. This cam may be lifted either by inserting the finger under the lip at 28, or by use of a screw driver or knife blade, as may be found convenient.

In Figure 5 I have illustrated a slightly modified form of the invention, which is similar in all respects to the other form above described, with the exception that the projection 20 and the apertured end for receiving the same has been eliminated and the curved portions are integral so as to provide a continuous circular portion 32 for receiving the post 11.

It will appear from the foregoing that I have contrived a very simple device which

may be connected to the post of a battery without danger of breaking the post and which is simple in its operation and cheap of manufacture.

5 Having described my invention, what I claim is:

A battery terminal device comprising means for gripping a battery post, cooperating straight portions formed with the post gripping means, links pivotally secured to one of the straight portions, conductor securing means formed with the last mentioned straight portion, a cam pivotally secured to the links and being engageable in a depression formed in the other straight portion for drawing the gripping means together, and said cam having a recess formed on its inner face adjacent its free end to provide a finger grip whereby the cam can be moved to inoperative position to permit spreading of the post gripping means.

In testimony whereof I affix my signature.

DANIEL H. SCHLAEGEL.
